UNITED STATES PATENT OFFICE.

HARRY M. THAYER, OF WOODHULL, ILLINOIS.

SECTIONAL ROOF CONSTRUCTION FOR SILOS.

1,083,157.

Specification of Letters Patent.

Patented Dec. 30, 1913.

Application filed January 20, 1913. Serial No. 743,132.

To all whom it may concern:

Be it known that I, HARRY M. THAYER, a citizen of the United States, residing at Woodhull, in the county of Henry and State of Illinois, have invented certain new and useful Improvements in Sectional Roof Construction for Silos, of which the following is a specification.

The present invention relates to certain new and useful improvements in roof constructions such as are adapted to be employed in connection with silos and similar structures, and has for its object to provide a roof which embodies novel features of construction whereby it can be readily opened up to uncover the top of the silo when such becomes necessary or desirable.

A further object of the invention is to provide a roof of this character which is comparatively simple and inexpensive in its construction, which can be readily mounted upon the silo or other structure, and which can be easily moved into either an open or a closed position.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a perspective view of a portion of a silo provided with a roof constructed in accordance with the invention, the said roof being shown in a closed position. Fig. 2 is a similar view showing the roof in an open position, the roof plate being removed from one of the roof sections to show the manner of constructing the frame thereof. Fig. 3 is an interior view of a portion of the roof, showing the position assumed by the parts when the roof is in a closed position. Fig. 4 is a similar view with the roof sections swung upwardly into an open position. Fig. 5 is a horizontal sectional view on the line 5-5 of Fig. 4. Fig. 6 is an enlarged detail view of one of the supporting brackets or castings and a portion of one of the roof sections, the said roof section being shown by full lines in the position assumed when in a closed position, and by dotted lines in the position assumed when swung upwardly into an open

position. Fig. 7 is a similar view of the opposite side of the supporting bracket or casting, showing a portion of an adjacent roof section, the said roof section being shown by full lines in the position assumed when closed, and the positions of the two adjacent roof sections when in a raised position being indicated by dotted lines, and Figs. 8 and 9 are detail perspective views of a pair of the supporting brackets or castings which are constructed in rights and lefts.

Corresponding and like parts are referred to in the following description and indicated in all the views of the drawings by the same reference characters.

Specifically describing the present embodiment of the invention, the numeral 1 designates the upper portion of a silo or similar structure upon which it may be desired to mount the roof, the said silo having a substantially circular top. The roof has a substantially conical formation when closed, and comprises an annular series of complementary triangular roof sections A and B, the said roof sections A and B being similar in construction and arranged alternately with respect to each other. Each of the roof sections A and B is formed of a triangular frame upon which the roof plate 2 is mounted. As indicated upon the drawings these triangular frames comprise the upwardly converging side pieces 3 which are connected at intermediate points in their lengths by the transverse cross bars 4. The roof plates 2 are preferably formed in the two triangular sections 2^a and 2^b, the edges of the sections overlapping at the center of the roof section and being riveted or otherwise connected to provide a seam 5. These longitudinal seams 5 serve to reinforce the roofing plates 2 at the center thereof.

The various roof sections A and B are mounted upon the supporting brackets 6 which are applied to the upper edge of the silo 1. Each of these supporting brackets 6 is shown as comprising a substantially vertically disposed base portion 6^a which is adapted to be fitted against and firmly connected to the inner face of the silo at the top thereof, and also with an upwardly and inwardly inclined seat 6^b upon which the roof sections A and B rest when in a closed position, the said seat 6^b and base portion 6^a being connected by the reinforcing web 6^c. It will also be observed that each of the

supporting brackets 6 is formed with a pair of outwardly projecting arms or wings 6^a and 6^b between which the side pieces 3 of adjacent roof sections A and B are received, 5 the arms 6^a being shorter than the arms 6^b and being shown as notched at the inner ends thereof as indicated at 6^c, so as to fit over and engage the upper edge of the silo. The supporting brackets 6, with respect to 10 the pivot arms 6^a and 6^b are formed in rights and lefts, as indicated by Figs. 8 and 9, and the various supporting brackets are designed to be applied to the top of the silo in an annular series so that the short arms 15 6^a and long arms 6^b of adjacent brackets will face each other. The side pieces 3 of the roof sections A are designed to be pivoted upon the short arms 6^a of the supporting brackets 6 in some suitable manner as by 20 means of the pivot bolts 7, while the side pieces 3 of the alternate roof sections B are designed to be pivoted upon the long arms 6^b in some suitable manner as by means of the pivot bolts 8. It will thus be obvious 25 that the pivot points of the roof sections B are disposed in a circle which is concentric with but somewhat larger than the circle in which the pivot points of the alternate roof sections A are disposed. In other 30 words, the pivot points 8 of the roof sections B are disposed outwardly farther away from the center of the silo than the pivot points 7 of the alternate roof sections A. Owing to this manner of pivoting the roof 35 sections A and B, all of the various roof sections can be swung upwardly into a substantially vertical position, as indicated by Figs. 2 and 4, the roof sections A which are pivoted upon the short arms 6^a being swung 40 upwardly first and the alternate roof sections B which are pivoted upon the long arms 6^b being subsequently swung upward. In a reverse manner, when closing the roof, 45 the roof sections B would first be swung inwardly and the roof sections A subsequently swung inwardly, all of the roof sections then co-operating with each other to produce a conical roof, as indicated by Figs. 1 and 3.

50 When the roof sections A and B are swung upwardly into a substantially vertical position, it will be observed that adjacent roof sections are slightly offset from each other, this feature being clearly brought 55 out by Fig. 5. This is a very important feature of the invention, since otherwise the lower corners of the triangular roof sections would interfere with each other and prevent the roof sections from being swung upwardly. The invention also contemplates 60 means for locking the various roof sections A and B in an upright or open position. For this purpose a series of tie rods 9 are provided, one end of each of the tie rods 65 being loosely connected at 10 to the edge

portion of one of the roof sections and being provided at its free end with a hook member 11 which is adapted to engage a keeper 12 upon the adjacent roof section. When these tie rods 9 are placed in operative position, as indicated by Fig. 4, the various roof sections A and B are securely locked together and retained in an upright or open position. When the roof sections are swung inwardly into a closed position these tie rods 9 hang loosely, as indicated by Fig. 3. It will be observed by reference to Fig. 4 that projecting keeper guards 12^a may be located on the roof sections adjacent the keeper 12 to act as abutments to prevent the hooked ends of the rods 9 from slipping through and past the keepers. 75 80

Having thus described the invention, what I claim as new and desire to secure by Letters Patent, is:—

1. A roof construction including an annular series of triangular roof sections hinged inward from their eaves ends so as to swing upwardly into an open position, alternate roof sections being mounted to swing about different centers so as to be offset from each other when swung upwardly. 90

2. A substantially conical roof including an annular series of complementary triangular roof sections, and supporting brackets adapted to be applied to the structure upon which the roof is mounted, the said roof sections being pivotally mounted inward from their eaves ends upon the supporting brackets so as to be swung upwardly into an open position and the said supporting brackets being formed with seats upon which the roof sections rest when swung inwardly into a closed position. 100

3. A substantially conical roof including an annular series of complementary roof sections, and a series of supporting brackets adapted to be applied to the structure upon which the roof is mounted, the brackets being each formed with a long arm and a short arm, and alternate roof sections being pivotally mounted upon the short arms, while intermediate roof sections are pivotally mounted upon the long arms, the various roof sections being adapted to be swung upwardly on pivots located inward from their eaves ends into an open position and adjacent roof sections being then offset from each other. 110

4. A substantially conical roof including an annular series of complementary triangular roof sections, and a series of supporting brackets adapted to be applied to the structure upon which the roof is mounted, each of the brackets being formed with a seat upon which the roof sections rest when swung inwardly into a closed position and with means for pivotally engaging the roof sections, adjacent roof sections being mounted 115 120 125 130 135

to swing on pivots located inward from their eaves ends and about different centers so as to be offset from each other when swung upwardly into an open position.

5. A substantially conical roof including an annular series of complemental triangular roof sections, and a series of supporting brackets adapted to be applied to the structure upon which the roof is mounted, said brackets being each formed with a seat upon which the roof sections rest when swung inwardly into a closed position and being also each formed with a long arm and a short arm, alternate roof sections being pivotally mounted upon the long arms of the brackets while the intermediate roof sections are pivotally mounted upon the short arms of the brackets so that adjacent roof sections will be offset from each other when the roof sections are swung upwardly into an open position on pivots located inward from their eaves ends.
- 10 15 20

6. A substantially conical roof including

an annular series of complemental triangular roof sections, and a series of supporting brackets adapted to be applied to the structure upon which the roof is mounted, the said supporting brackets being formed in rights and lefts and being each formed with a long arm and a short arm, so that adjacent brackets present the long arms and short arms in pairs, alternate roof sections being pivotally mounted upon the long arms while the intermediate roof sections are pivotally mounted upon the short arms, the various roof sections being adapted to be swung upwardly into an open position on pivots located inward from their eaves ends and alternate roof sections being then offset from each other.

In testimony whereof I hereunto affix my signature in the presence of two witnesses.
